UNITED STATES PATENT OFFICE.

WILLIAM HENRY MUNN, OF MILWAUKEE, WISCONSIN.

DESIGN FOR A BURNER FOR OIL OR GAS STOVES.

SPECIFICATION forming part of Design No. 19,641, dated February 11, 1890.

Application filed January 11, 1890. Serial No. 336,698. Term of patent 7 years.

To all whom it may concern:

Be it known that I, WILLIAM HENRY MUNN, a citizen of the United States, residing at Milwaukee, in the county of Milwaukee and State 5 of Wisconsin, have invented and produced a new and original Design for Gas-Burners for Gas-Stoves; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 Figure 1 is a view in perspective showing my design. Fig. 2 is a sectional view on line $x x$, Fig. 1.

20 The leading feature of my design of a burner for oil or gas stoves consists in its horseshoe form with interior and exterior walls having perforations along or near their upper edges, a downwardly-extending neck curving off in a line parallel with its under side and with raised ends on its upper side corresponding with the frogs upon the ordinary 25 horseshoe.

A is the design of my burner, showing the

form of an ordinary horseshoe. a and b are the interior and exterior walls of the same. c and d are perforations along or near the upper edges of these walls; and C , D , and E are the raised ends or projections on its upper side, corresponding in form and position to those upon the ordinary horseshoe, all as clearly shown in Fig. 1. 35

B is a neck opening into the under side of the curved end of the burner, and extending downward and then curving off in a line parallel with its under side, as shown in Fig. 2.

Having thus described my design, what I 40 claim, and desire to secure by Letters Patent, is—

The design for an oil or gas stove burner herein shown and described, the same comprising the horseshoe-shaped burner with the 45 perforations c and d along its exterior and interior walls and curved neck B, as set forth.

In testimony whereof I affix my signature in presence of two witnesses.

WILLIAM HENRY MUNN.
